(57) **CLAIM**

The ornamental design for the medical liquid tubing clamp, as shown and described.

DESCRIPTION

FIG. 1 is a front plan view of the medical liquid tubing clamp; FIG. 2 is a back plan view of the medical liquid tubing clamp; FIG. 3 is a front perspective view of the medical liquid tubing clamp;

FIG. 4 is a rear perspective view of the medical liquid tubing clamp;

FIG. 5 is a right side view of the medical liquid tubing clamp; FIG. 6 is a left side view of the medical liquid tubing clamp; FIG. 7 is a top view of the medical liquid tubing clamp;

FIG. 8 is a bottom view of the medical liquid tubing clamp; and,

FIG. 9 is a perspective view of the medical liquid tubing clamp in a closed position.

The broken lines illustrate environmental structure of the medical liquid tubing clamp, which forms no part of the claimed design.
